Primary Examiner—Wallace R. Burke*Assistant Examiner*—Lisa Lichtenstein*Attorney, Agent, or Firm*—Julian Caplan[57] **CLAIM**

The ornamental design for a lazarette cushion, as shown and described.

DESCRIPTION

FIG. 1 is a top plan view of my new lazarette cushion; FIG. 2 is a bottom plan view thereof; and, FIG. 3 is a perspective view showing the top, one side and the front thereof; the side opposite that shown and the rear are the same as the side shown and the front, respectively.

The cross hatching in FIGS. 1-3 represents conventional fabric and is understood to extend uniformly throughout the surfaces of the cushion.

FIG. 1

FIG. 2

FIG. 3
